FIG. 5.

INVENTOR

Charles A. Brewer
BY *John R. Knight*

ATTORNEY

UNITED STATES PATENT OFFICE.

CHARLES A. BREWER, OF NOROTON HEIGHTS, CONNECTICUT, ASSIGNOR TO ADJURIA INCORPORATED, A CORPORATION OF DELAWARE.

FIRST-AID KIT.

1,337,433.

Specification of Letters Patent. Patented Apr. 20, 1920.

Application filed July 2, 1919. Serial No. 308,225.

To all whom it may concern:

Be it known that I, CHARLES A. BREWER, a citizen of the United States of America, residing at Noroton Heights, county of Fairfield, and State of Connecticut, have invented certain new and useful Improvements in First-Aid Kits, of which the following is a specification.

My invention is intended for the use of 10 travelers, and is particularly designed to be affixed to automobiles, or motor cars as an accessory; incidentally I provide a bracket for supporting and retaining the kit in position in the automobile, or motor car, and I 15 intend, as a part of my device, when commercially introduced, to supply a duplicate bracket to be placed in a residence, or elsewhere, so that the kit itself can be shifted from one bracket to the other, as may be 20 desired.

It is the intent and purpose of my invention to provide a complete set of first aid devices and medicines, and in carrying my invention into effect, I employ an inclosing 25 envelop consisting of two members, both cup shaped in construction; when brought together end to end, their meeting faces can be sealed water tight by an interiorly disposed locking arrangement; on which locking arrangement is a diaphragm whose rim extends beyond the edges of the cups, and against which the said edges are brought 30 and sealed tightly by the locking device aforesaid.

35 This locking device consists of a tray in which most of the implements and medicines are suitably arranged, it being provided with compartments to retain the same in position, and openings to afford access for 40 the fingers when it is desired to remove any particular item.

Various other features are embodied in my invention, which, although I have shown and described it as a first aid kit, really constitutes a container, as will be explained. In order more fully to understand my invention, I will proceed to describe it in connection with the accompanying drawings, which form a part of this specification, and 45 in which Figure 1 represents a vertical section of the container, showing it in position in a supporting bracket, the said bracket likewise being shown in vertical section; in this figure some of the parts, such as the tray 50 and its contents, are shown in elevation.

Fig. 2 shows the tray with its contents removed from the casing. Fig. 3 is a cross section on the line III—III, Fig. 1. Fig. 4 is a detail view. Fig. 5 is an end view of the tray.

In these drawings 10 is the upper, and 11 the lower section of the casing, or envelop, of the container. These sections are cup shaped, and when brought to position for 60 assembling, are arranged with the open faces toward each other; when disassembled, however, and their contents removed, they can be used for serving, or measuring, liquids or for other purposes.

12 is a bracket secured by any proper 70 means, such as the screws 13 to the wall 14, and which bracket is cup shaped, and is adapted to receive the container as shown in Fig. 1 when the latter is properly introduced, and will retain it in an upright position, the spring pieces 15 serving to press 75 the container over against the pads or non-abrasive strips 16, in the manner hereinafter described; these pads or strips act also as guides for the entrance or removal of containers; this arrangement also will prevent the jarring and shaking loose both of the container and its contents.

When it is desired to remove the container, it can be easily pulled upward, 80 against the spring 15. At 18 I provide a cushion on which the lower part of the container rests, and which is utilized to absorb or arrest vertical vibration. This cushion is placed in a suitable pocket in the lower 85 part of the bracket 12. At 19 are legs on which the part 10 can be supported when it is disassembled from the part 11, and its position reversed, and it is used as a cup or measuring device for liquids. These legs 90 are preferably four in number.

I will now proceed to describe the locking agency 20, which is inclosed within the container, and which constitutes also a tray on or in which the various elements and devices of the kit are supported, or held. This tray, shown with its contents in Fig. 2, is removable as a whole, and when removed 100 can be supported in a horizontal position as shown in Fig. 5, the legs 21 being provided 105 to steady the same and prevent it from rolling. When the tray is in position as in Fig. 1 the springs 15 register against the upper edges of the legs 21 and the tray being interlocked with the casings the unit thus as- 110

sembled will be properly retained by the springs.

At 22 and 23 are screws attached to and extending inwardly from the bottom of the casings 10 and 11 and by means of these screws the two casings are adapted to be attached to the tray 20 and when brought home the edges 17 and 24 of the casings will be drawn up tightly against the rim 25 of the 10 diaphragm 26. When so positioned, the said casings, 10 and 11, with the rim 25, will present a continuous water tight surface for the entire apparatus.

It is to be understood that these screws 22 15 and 23, constitute absolute locking means for securing the parts, heretofore described, tightly together; a mere friction hold, or any means short of the tight lock, would be insufficient for my purposes as my apparatus is subjected to considerable jarring in 20 transportation; furthermore a tight screw joint lock is necessary in order to draw the parts together to render the structure impervious to outside moisture.

25 The diaphragm 26 is formed integrally with the tray 20 and divides the tray into two zones, one of said zones being utilized for holding implements and the other for holding bottles for medicines.

30 In the upper or larger zone, I dispose as stated the implements as shown in Figs. 1, 2 and 3, a specially designed compartment being shown at 27 for safety pins, which compartment has a hinge door, 28, and in 35 the frame of the door I provide an additional small compartment for needles as shown at 29. Another compartment is shown at 30 for scissors and like articles; at 31 is a dropper; the central section 32 40 is reserved for fibrous material of different sizes; outside and at the end of the larger zone is a reel 33 for binding tape.

In the smaller zone partitions 34 are provided with collars 35 to retain bottles 36 in 45 place; the collar 35 being positioned to hold down the shoulders 37 of the bottles; recesses 38 are shown so as to provide access for the fingers.

At 39 is a spool for thread or other material.

At 40 is a sleeve for retaining the contents of the smaller zone in place; this sleeve is provided with flanges 41 extending outwardly and registering with the inner surface 55 of the casing 11; on the outer face of the sleeve 40 I attach in any suitable manner first aid directions; the flanges 41 afford means for protecting same and prevent their being torn off or otherwise dislodged.

60 At 42 and 43 on the larger zone I place sealing sleeves also, the sleeve 42 having flanges 44 providing an annular chamber for splints 45. These sleeves also provide means for maintaining the contents of the 65 larger zone in position, holding them in po-

sition when the two part casing is being unscrewed.

The flutings 46 of the casings afford means for grasping them and unscrewing them from the binding agency, but if it becomes necessary, a wrench can be used on either hexagon 47 at the outer ends of the casings.

I claim:

1. A container embodying two cup-shaped 75 casings disposed, when assembled, with their open faces opposed, and a core having a rimmed diaphragm positioned between the casings providing a locking agency.

2. A container embodying two cup-shaped 80 casings, a core providing a tray and locking means at both ends of the tray to secure the cups together and to the prescribed shape.

3. A container embodying two cup shaped 85 casings, an inclosed tray, and means for drawing the open facings of the casings toward each other and providing a water tight joint.

4. A container embodying two cup shaped 90 casings, an inclosed tray, means on the ends of the tray, and coördinating means on the inside of the casing ends for drawing said casings together and securing them to the tray.

5. A container embodying two cup-shaped casings, an inclosed tray having a diaphragm externally rimmed, and means for drawing and tightening the open faces of the casings against the rim, providing a 100 water tight joint.

6. A container embodying an outer casing of two cup shaped vessels disposed, when assembled, with their open ends facing each other, and an inclosed tray affording a 105 locking agency for the vessels, and means in the tray and vessels providing a complete envelop and housing for the container contents.

7. A container embodying two cup-shaped 110 vessels each capable of separate use when disassembled, with an inclosed connecting and locking structure embodying a tray.

8. A container formed of two cup-shaped vessels disposed when assembled with their 115 open faces opposite each other, a tray inclosed in said cups and provided with a dividing diaphragm situated between the edges of the cups when assembled, and means upon each end of the tray structure 120 for locking the cups together and against the diaphragm.

9. A two-part container having a tray provided with suitable pockets, or receptacles, passages in each receptacle for facilitating quick removal of contents, means at each end of the tray for securing and locking in position the two part container constituting the tray covering envelop.

10. A container embodying an inclosed 130

tray, a spool structure attached thereto at one end, and means for winding and unwinding on said spools, thread or other material.

5 11. A container embodying a tray having a safety pin receptacle, a hinged cover therefor, a needle pocket in said cover, and a cover retaining spring.

10 12. A container embodying a tray having bottle holding receptacles, lugs formed integrally therewith and so positioned as to register the bottle necks and corks in safety positions, and prevent the insertion of bottles in any but said upright positions.

15 13. A container provided with a centrally disposed locking tray, a sleeve for retaining first-aid units in position, said sleeve having outwardly flaring flanges at each edge providing thereby means for protecting 20 printed lists of contents and first aid directions.

25 14. A container embodying a tray having pockets, or receptacles, therein, a retaining sleeve telescoped over said tray in such a manner as to prevent egress and breakage

of the contents of the tray, with tray inclosing casings, and means for securing the casings to the tray.

15. A container embodying a tray, receptacles therein, finger passages providing access to said passages, a retaining sleeve telescoping over the tray and a second sleeve of larger diameter telescoping over the retaining sleeve and providing between the sleeves an intermediate receptacle for splints and like articles.

16. A container having two vessels, a tray positioned therein, a tray dividing diaphragm providing two compartments in the tray, and sealing sleeves for the two compartments.

17. The combination in a container of two cups or casings, an inclosed tray having a diaphragm positioned when assembled between the edges of the cup and means on said diaphragm consisting of legs to prevent the tray from rolling when the parts are disassembled.

CHARLES A. BREWER.
